UNITED STATES PATENT OFFICE.

JOHN C. DORDEA, OF DETROIT, MICHIGAN.

PENCIL AND SHARPENER.

1,165,856.

Specification of Letters Patent. Patented Dec. 28, 1915.

Application filed September 4, 1915. Serial No. 48,957.

To all whom it may concern:

Be it known that I, JOHN C. DORDEA, a subject of Austria-Hungary, residing at Detroit, in the county of Wayne and State of Michigan, have invented certain new and useful Improvements in Pencils and Sharpeners, of which the following is a specification, reference being had therein to the accompanying drawings.

10 This invention relates to pencils, and the primary object of my invention is to provide a lead or graphite holder wherein means are combined for adjusting the lead relative to the holder and sharpening or 15 scraping the end of the lead, when in a retracted position, to provide the same with a point which may be used when the lead is extended relative to the holder.

Another object of my invention is to provide a lead or graphite holder with permanent concealed sharpening or scraping devices which can be easily and quickly brought into action to sharpen or scrape a piece of lead or graphite within the holder 25 by simply rotating a portion of the holder.

A further object of my invention is to accomplish the above result by a durable mechanical construction that will be herein-after specifically described and then 30 claimed, and reference will now be had to the drawing, wherein—

Figure 1 is an enlarged longitudinal sectional view of a pencil in accordance with my invention; Fig. 2 is an enlarged longitudinal sectional view of the writing end of 35 the pencil, showing the lead or graphite in a retracted position to be sharpened or scraped; Fig. 3 is a cross sectional view taken on the line III—III of Fig. 2; Fig. 4 is a similar view taken on the line IV—IV of Fig. 1; Fig. 5 is a similar view taken on the line V—V of Fig. 1; Fig. 6 is a similar view taken on the line VI—VI of Fig. 1; and Fig. 7 is a similar view taken on the 45 line VII—VII of Fig. 1.

In exterior appearance the pencil comprises a point section 1, a hand section 2, a lead retracting section 3, and a lead extending section 4. All these sections are cylindrical and the sections 3 and 4 may be knurled to facilitate rotating the same. The lead extending section 4 has an inner end wall 5 provided with a clearance tube 6 and adjacent the wall 5 is a collar 7 integral 55 with the tube 6. Between the wall 5 and the collar 7 is a cylindrical head 8, which as

shown in Fig. 7, is split or slotted as at 9, whereby the head may be sprung over the collar 7 to loosely engage the clearance tube 6. The head 8 is exteriorly screwthreaded 60 and is mounted in one end of the lead retracting section 3.

The inner end of the clearance tube 6 is cut and bent to provide an inwardly projecting lug 10, and this lug extends into a 65 longitudinal slot 11 provided therefor in a nut tube 12 slidable in the clearance tube 6. By reason of the lug 10 extending into the slot 11, the tubes 6 and 12 are arranged for rotative continuity when the lead extending 70 section 4 is rotated. The inner end of the nut tube 12 terminates in a nut portion 13 in screwthreaded engagement with a screw 14 disposed longitudinally of the nut tube 12.

The inner end of the lead retracting section 3 is provided with an exteriorly screwthreaded sleeve 15 free to revolve upon the clearance tube 6. The sleeve 15 has a longitudinal slot 16 and is in screwthreaded engagement with an end of an inner barrel 17. 80 This barrel is slidable longitudinally of an outer barrel 18 fixed by a pin 19 in the hand section 2. The outer barrel has a longitudinal slot 20, and into this slot extends a pin 21 carried by the inner barrel 17, said pin 85 preventing the inner barrel 17 from rotating relative to the outer barrel 18.

Screwed into the end of the hand section 2 is a bushing 22 in which the sleeve 15 revolves, and said hand section 2 is screwed 90 on a cylindrical bearing 23 supporting a tubular lead or graphite holder 24. The holder 24 longitudinally alines with the nut tube 12 and said holder is adapted to contain a piece of lead or graphite 25 having 95 the inner end thereof engaged by the screw 14. The inner end of the holder 24 has a head 26 and said head and the nut portion 13 of the nut tube 12 have annular grooves 27 for stirrups 28 forming part of a coupling member 29, said coupling member retaining the holder 24 and the nut tube 12 in spaced relation, yet allowing the nut tube to freely revolve relative to the holder 24. The stirrups 28 can be easily placed in the 100 annular grooves 27 and to retain said stirrups therein, the coupling member 29 has a pin 30. One end of the pin extends into a longitudinal groove 31 provided therefor in a screw 14, said groove having closed ends 110 whereby the screw cannot become accidentally displaced relative to the pin 30. The

pin 30 also prevents a rotative movement of the screw relative to the nut tube 12 and in order that said pin can be easily installed, it has an intermediate nut portion 32. The 5 pin 30 also holds a finger 33 on the coupling member 29 and said finger extends into the longitudinal slot 16 of the sleeve 15, thereby establishing rotative continuity between the sleeve 15 of the lead retracting section 10 3 and the coupling member 29.

The inner barrel 17 has diametrically opposed walls thereof cut away, as at 34, to reduce the weight of said barrel and the remaining portions of said barrel are provided with inwardly projecting arms 35 engaging the head 26 of the holder 24. The holder 24 has a longitudinal groove 36 and extending into said groove is a pin 37, carried by the bearing 23. A reduced portion 15 of the bearing 23 supports a head 38 and a ferrule 39, the former being screwed in the point section 1 of the pencil. Abutting the ferrule 39 are the semi-cylindrical portions 40 of opposed sharpeners or scrapers 20 41 which are held in position by pins 42, carried by the point section 1 and engaging the semi-cylindrical portions 40 of the sharpeners or scrapers. The sharpeners or scrapers are resilient and have splitted ends 25 43 beveled, as at 44, and normally held in a retracted position by a spherical or globular expanding member 45 on the holder 24.

The writing end of the pencil terminates in a conical portion 46 of the point section 35 1, said conical portion serving as a guide for the reciprocable holder 24. In order that the lead or graphite 25 will not become accidentally displaced relative to said holder, the outer end of the holder is slotted, 40 as at 47 to frictionally engage the lead or graphite.

In operation, I will first assume that the pencil is in position to be used and that it is desired to retract the holder 24 and the 45 lead or graphite 25 thereof, whereby the pencil can be carried in the pocket without danger of the lead or graphite point being broken. To retract the holder 24, the lead retracting section 3 is rotated and as the 50 sleeve 15 is revolved, the inner barrel 17 is shifted inwardly and through the medium of the arms 35 engaging the head 26, the holder 24 is moved inwardly, carrying with it the lead or graphite 25. This is accomplished by two or three revolutions of the 55 lead retracting section 3 which are sufficient to withdraw the point of the lead or graphite. Assuming again that the pencil has been used and the lead or graphite has become dull and requires sharpening. The 60 lead extending section 4 is now rotated and a rotary movement imparted to the nut tube 12, which forces the screw 14 outwardly, thereby pushing the lead or graphite 25 outwardly in the holder 24. This operation

presents sufficient lead or graphite at the outer end of the holder whereby it may be sharpened or scraped. The adjustment of the lead or graphite having been accomplished, the lead or holder retracting section 70 3 is now rotated until the inner barrel 17 has been retracted as far as possible. During this movement, the nut tube 12 slides in the clearance tube 6 and the coupling member 29 is prevented from shifting relative to 75 the nut tube 12 by reason of the finger 33 extending into the slot 16 of the sleeve 15. As the holder 24 is retracted, the expanding member 45 releases the scrapers 41, as best shown in Fig. 2, thereby placing the sharpening or scraping edges of the scrapers in engagement with the lead or graphite 25. Now, by rotating the hand section 2 the holder 24 is revolved and in consequence of this movement the end of the lead or graphite is scraped against and sharpened by the beveled edges of the scrapers. Restoring the inner barrel 17 to a position intermediate the ends of the hand section 2 expands the scrapers 41 and by further shifting the inner barrel 17 the holder 24 emerges from the conical end 46 of the pencil and presents a sharpened lead or graphite point for writing purposes. 80

A spanner wrench can be used for assembling certain elements of the pencil, and it is thought that the operation and utility of the same will be apparent without further description. While in the drawing there is illustrated a preferred embodiment 100 of my invention, it is to be understood that the structural elements are susceptible to such variations and modifications as fall within the scope of the appended claims. 95

What I claim is:—

1. A pencil comprising cylindrical sections, a revolvable bearing in one of said sections, a reciprocable lead holder in said bearing and adapted to be revolved thereby, resilient scrapers in another section of said pencil to engage the lead of said holder, means on said holder to maintain said scrapers normally out of engagement with said holder, and means in another section of said pencil to reciprocate said holder in 115 said bearing.

2. A pencil comprising cylindrical sections, a bearing in one of said sections, a holder reciprocable in said bearing, a lead in said holder, sharpening means in another section, means on said holder to maintain said sharpening means normally out of engagement with said holder, and means in another section to move said holder and release said sharpening means whereby said lead is positioned to be engaged by said sharpening means. 120

3. A pencil comprising sections, a bearing in one of said sections, a holder slidably in said bearing, a lead in said holder, re- 130

- 5 slient sharpening means in another section maintained normally out of engagement with said lead by said holder, a barrel in another section to move said holder whereby said sharpening means may engage said lead, means forming a part of another section to impart movement to said barrel, and means axially of said barrel to move said lead independently of said holder.
- 10 4. A pencil comprising a point section, a hand section, a holder retracting section and a lead extending section, sharpening means in said point section, a lead holder in said point section, a lead in said holder, sharpening means in said point section held out of engagement with said lead by said holder, a barrel in said hand section to move said holder and the lead thereof whereby said sharpening means is released to engage said lead, means forming part of said holder retracting section to move said barrel, and means actuated by said lead extending section and extending into said holder to move said lead independently thereof.
- 15 5. A pencil comprising a point section, a hand section, a holder retracting section, and a lead extending section, a lead movable axially of said point section, sharpening means in said point section, means for holding said sharpening means normally out of engagement with said lead, means actuated in the other sections of said pencil to release said sharpening means to engage said lead, and means axially of the other sections to move said lead independently of the releasing means of said sharpening means.
- 20 6. A lead pencil comprising a point section, a hand section, a holder retracting section, and a lead extending section, a lead in said point section, holding means therefor, means in said hand section actuated by said holder retracting section to impart movement to said lead holding means, and means actuated by said lead extending section to impart movement to said lead independently of said lead holding means.
- 25 7. A pencil comprising a point section, a hand section, a holder retracting section, and a lead extending section, a bearing in said point section, a reciprocable lead holder in said bearing, a lead in said holder, sharpening means in said point section, maintained normally out of engagement with said lead by said holder, a barrel in said hand section actuated by said holder retracting section to move said holder and release said sharpening means, a screw extending into said holder to move said lead independently thereof, and means including a nut tube actuated by said lead extending section to move said screw.
- 30 8. A pencil comprising a point section, a hand section, a holder retracting section, and a lead extending section, a bearing in said point section, a reciprocable lead holder in said bearing, a lead in said holder, sharpening means in said point section, means on said holder to hold said sharpening means normally in a retracted position relative to said holder, an inner barrel in said hand section to reciprocate said holder and release said sharpening means, means actuated by said holder retracting section for moving said barrel, a nut tube in said hand section coupled to said holder, a screw in said nut tube extending into said holder to move said lead independently thereof, and a clearance tube actuated by said lead extending section to receive said nut tube and impart a rotary movement thereto.
- 35 9. A pencil comprising a point section, a hand section, a holder retracting section, and a lead extending section, a clearance tube carried by said lead extending section and extending through said holder retracting section, a nut tube extending into said clearance tube, a screw in said tube to be reciprocated by a rotary movement of said lead extending section, a bearing in said point section, a lead holder reciprocable in said bearing, a lead in said holder, a coupling member connecting said lead holder and said nut tube, an outer barrel mounted in said hand section, an inner barrel reciprocable in said outer barrel to move said lead holder, a sleeve carried by said holder retracting section to move said inner barrel, resilient sharpeners in said point section, and an expander on said lead holder maintaining said sharpeners normally out of engagement with said lead holder.
- 40 10. A pencil comprising a point section, a hand section, a holder retracting section, and a lead extending section, a clearance tube carried by said lead extending section and extending through said holder retracting section, a nut tube extending into said clearance tube, a screw in said nut tube to be reciprocated by a rotary movement of said lead extending section, a bearing in said point section, a lead holder reciprocable in said bearing, a coupling member connecting said lead holder and said nut tube, means in said hand section and actuated by said holder retracting section to impart movement to said lead holder, resilient sharpeners in said point section, and an expander on said lead holder maintaining said sharpeners normally out of engagement with said lead holder.
- 45 11. A pencil comprising a point section, a hand section, a holder retracting section, and a lead extending section, a clearance tube carried by said lead extending section and extending through said holder retracting section, a nut tube extending into said clearance tube, a screw in said nut tube to be reciprocated by a rotary movement of said lead extending section, a bearing in said point section, a lead holder reciprocable in said

4
bearing, a coupling connecting said lead holder and said nut tube, an outer barrel mounted in said hand section, an inner barrel reciprocable in said outer barrel to move said lead holder, a sleeve carried by said holder retracting section to move said inner barrel, a finger on said coupling member engaging said sleeve to cause said coupling member to rotate with said sleeve, resilient sharpeners in said point section, and

an expander on said lead holder maintaining said sharpeners normally out of engagement with said lead holder.

In testimony whereof I affix my signature in presence of two witnesses.
